Inventor
George O. Reshaw.
By Eugene M. Giles *Ph.D.*

UNITED STATES PATENT OFFICE

GEORGE OTIS RESHAW, OF LOS ANGELES, CALIFORNIA

BASKET

Application filed April 18, 1927. Serial No. 184,521.

My invention relates to stave baskets and containers such as are used in packing vegetables, fruits and the like and particularly to such type of basket wherein the staves are 5 scored or otherwise formed so that the free ends of each stave may be bent upwardly at an angle to the intermediate portion of the stave and form substantially upright or straight sides for the basket. The intermediate portions of the staves are bowed or arched to form the bottom of the basket.

One of the objects of my present invention is to provide means for supporting and reinforcing the angularly bent portions of 15 the staves so as to prevent not only outward spreading of the lower upright walls of the basket but also to provide a strong support for the arched portions of the staves which constitute the bottom of the basket.

Another object of my invention is to provide a support of this nature which will not only completely embrace and house these angularly bent portions of the staves and thus reinforce and protect them from wear or 25 damage during use, but which will also provide a ledge to receive the outward thrust of the basket load and at the same time provide a strong supporting bottom upon which the basket rests.

These and other objects of my invention will be apparent from the following specification when taken in connection with the accompanying drawing wherein,

Fig. 1 is a plan view of my improved basket;

Fig. 2 is a side elevation thereof, with certain parts broken away to show other parts in section;

Fig. 3 is an enlarged sectional detail of the 40 reinforcing means for the angularly bent portions of the stave.

In the type of basket to which my invention particularly applies, the basket is formed of a plurality of staves of wood or other material. Each stave is bent angularly preferably by scoring at two points, one of which 45 bends is shown at 4 in Fig. 2 of the drawing, to provide a base or bottom portion 6 and two diametrically opposed upstanding portions 8 and 10. The base portions 6 of the

staves overlap and form the bottom of the basket, while the upstanding portions 8 and 10, which are also preferably overlapped, form the side wall of the basket. The side wall is reinforced at appropriate points by 55 bands or hoops 12 and 14. As a result of the foregoing construction the side wall of the basket is formed substantially straight with respect to the bottom of the basket and the base portions of the staves are arched or 60 bowed upwardly, thereby eliminating the lower round cornered bend of the staves and permitting the weight to be taken directly upon the ends of the staves, while also affording a raised bottom for the basket. 65

My present invention consists in providing reinforcing means for the angularly bent portions 4 of the staves and particularly reinforcing means which completely embraces portions of both the upright and bottom walls adjacent the bend 4. 70

In my present invention I provide a metal band 16, which is angular or somewhat L-shaped in cross section, so as to afford two supporting walls, one adapted to embrace the 75 upstanding portions of the staves and support them, and the other to provide a ledge or lower wall 18 for underlying and supporting the outer portions of the arch shaped parts 6 of the staves which constitute the 80 bottom of the basket. This reinforcing band 16 forms a complete housing and support for the angularly bent portions of the staves and prevents breakage thereof due to excessive strains or loads. In addition the reinforcing means forms a bottom support upon 85 which the basket rests. This metallic band 16 is secured by nails or staples 20 or otherwise, to certain of the staves and rigidly embraces the lower ends of all of the vertical portions of the staves, while the bottom ledge 18, which is angularly disposed to the vertical wall of the band 16 not only forms a 90 ledge or seat for the ends of the bottom portions of the staves, but stiffens the upright portions of the band 16 to maintain the circular form thereof and prevent distortion 95 of the bottom edge of the basket due to unequal inside pressure or external strains.

While I have shown and described my in- 100

vention in a preferred form, I am aware that various changes and modifications may be made without departing from the principles of my invention, the scope of which is to be determined by the appended claims.

5 I claim as my invention:

1. In a basket, a plurality of elastic wood splints arranged and bent to form a tub basket, a central part of each of the splints 10 extending across the bottom and the end portions of the splints extending along the sides of the basket, a pair of hoops for holding the said splints in substantially cylindrical form, a metal L-shaped band covering the bottom corner of the basket, the bottom splints extending in parallel planes and the external diameter of the bottom having a diameter larger than the outside diameter of the L-shaped hoop before the hoop is applied, the 15 central portions of the splints curved inwardly and operating by their elasticity to engage the metal band and the metal band operating to hold the outside of the bottom of the basket formed by the central parts of the 20 splints concave as against their elasticity.
2. A tub basket comprising a plurality of staves each having a central portion extending across the bottom of the basket and end portions bent upwardly at an abrupt angle 25 to the central portion to form the sides of the basket, a plurality of hoops holding the staves in substantially cylindrical form and one of said hoops being of substantially L-shape in cross section and covering the bottom corner of the basket, the said central portions of the staves being longer than the diameter of the basket bottom and held in upwardly bowed form by engagement of the 30 ends thereof in the corner of the aforesaid L-shaped hoop.
